UNITED STATES PATENT OFFICE.

ANTHONY BARTH, OF CHICAGO, ILLINOIS, ASSIGNOR TO WOODRUFF & EDWARDS COMPANY, OF ELGIN ILLINOIS, A CORPORATION OF ILLINOIS.

DESIGN FOR A LAMP BASE.

Application filed July 28, 1926. Serial No. 18,526. Term of patent 3½ years.

To all whom it may concern:

Be it known that I, ANTHONY BARTH, a citizen of the United States, resident of Chicago, in the county of Cook and State of Illinois, have invented a new, original, and ornamental Design for Lamp Bases (Case 1), of which the following is a specification, reference being had to the accompanying drawing, forming part thereof.

Fig. 1, is a plan view of my novel design of lamp base, the view showing the complete outline, though only a portion or a

segment of the ornamentation appears thereon, it should be understood, however, that the balance of the unornamented portion within the outline involves a mere repetition of that portion more fully illustrated; and

Fig. 2, is a side elevation of the base.

I claim:

The ornamental design for a lamp base as shown.

ANTHONY BARTH.
